UNITED STATES PATENT OFFICE.

DAVID HOIT, OF WEST ALBANY, NEW YORK, ASSIGNOR OF ONE-HALF OF HIS RIGHT TO ALLEN MIDDLETON, OF PHILADELPHIA, PA.

DRAW-BAR FOR RAILWAY-CARS.

SPECIFICATION forming part of Letters Patent No. 225,132, dated March 2, 1880.

Application filed January 5, 1880.

To all whom it may concern:

Be it known that I, DAVID HOIT, a citizen of the United States, residing at West Albany, Albany county, New York, have invented an improvement in Draw-Bars for Railroad-Cars, of which the following is a specification.

My invention consists of certain improvements, fully described hereinafter, in draw-bar mechanism for railway-cars, the main object of my improvements being economy in construction and the relief of the frame of the car from the injurious effects of the shocks and strains to which said frames are subjected.

In the accompanying drawings, Figure 1 is a vertical section of sufficient of the framework of a railway-car to illustrate my improved draw-bar mechanism, and Fig. 2 an inverted plan view of Fig. 1.

A A are the two end or bumper beams of the car-frame, and B B two intermediate transverse beams, situated one on each side of and a short distance from the center line x x of the frame. All these beams are permanent parts of the frame-work, being secured to the central longitudinal beams, D D, and to the side beams, the latter not being shown in the drawings.

Between the two central transverse beams, B B, extend the bars M, which are secured to the longitudinal beams D D, the bolts e e, referred to hereinafter, passing through the said transverse beams.

Two blocks, E E, are secured to the longitudinal beams D D, one block being arranged at a short distance from each bumper-beam, and between each block and that transverse beam B which is nearest to it intervene bars a a, situated below and secured to the longitudinal beams D D.

At each end of the car-frame is a bumper and draw-head, G, adapted to guides b b, secured to the frame, and to each draw-head is secured a rod, H, which extends through the block E, through the space between the bars a a, and through one of the transverse beams B, between which and a nut on the end of the rod intervenes a spiral spring, I, consisting, in the present instance, of two coils arranged one within the other, a similar spring, J, interven-

ing between the inner end of each bumper-block and the adjoining block E.

When a car provided with the above draw-bar mechanism is started the tensile strain will, in the first instance, and for a moment, be exerted on that draw-bar to which the pulling force is applied, and this first strain will be resisted by both transverse beams B B; and as these are intimately connected together by the bolts e e, and are permanently incorporated with and form a part of the entire frame, the effect of this first shock will be distributed throughout the frame, and this effect will be modified by the yielding of one of the springs I.

Immediately after this first pulling shock, and when the slack of the coupling-link which connects the car to an adjoining car has been taken up, there will be an outward pulling strain on both bars in contrary directions, and this will tend to force the transverse beams B B apart; but as these beams are connected together by the bolts e e the latter have actually to resist the tension from which the frame is thus relieved.

In bumping, the force is first exerted on one of the springs J, and one of the blocks E; but there is such an intimate connection of the two blocks E E, through the medium of the bars a a and M M, that the shock, modified by the yielding of the spring, will be distributed throughout and absorbed by the entire frame.

I claim as my invention—

The combination, in a car-frame, of two disconnected draw-rods, H H, one secured to a draw-head at one end of the car and the other to a draw-head at the opposite end of the car, with the two central transverse beams B B, connecting-bolts e e, and the two springs I I, one for one draw-bar and the other for the other draw-bar, all substantially as set forth.

In testimony whereof I have signed my name to this specification in the presence of two subscribing witnesses.

DAVID HOIT.
